UNITED STATES PATENT OFFICE

129,724

DESIGN FOR A DESK CABINET

Roscoe R. Gardner, Glenrock, Wyo.

Application July 26, 1941, Serial No. 102,513

Term of patent 7 years

To all whom it may concern:

Be it known that I, Roscoe R. Gardner, a citizen of the United States, residing at Glenrock, in the county of Converse and State of Wyoming, have invented a new, original, and ornamental Design for a Desk Cabinet, of which the following is a specification, reference being had to the accompanying drawing, forming part thereof.

I claim:

The ornamental design for a desk cabinet, as shown.

ROSCOE R. GARDNER.
